Specification of Letters Patent.

Patented June 2, 1914.

Application filed August 2, 1912. Serial No. 712,907.

To all whom it may concern:

Be it known that I, EDWARD J. F. REA, a citizen of the United States, residing at Hartford, in the county of Hartford and 5 State of Connecticut, have invented certain new and useful Improvements in Printing-Presses, of which the following is a specification.

This invention relates to printing presses 10 and especially to a means for operating a form-carrier, one of the principal objects of the invention being to provide simple and effective means of the character indicated by which a form can be caused to move toward 15 and from the printing plane.

In the drawings accompanying and forming part of the present specification I have shown in detail one of the several convenient forms of embodiment of the invention, which 20 I will set forth in detail in the following description, this showing being primarily provided to enable those skilled in the art to practise the invention. It will be clear that I do not restrict myself to such disclosure; 25 I may depart therefrom in several respects within the scope of the invention defined by the claims following said description.

Referring to the drawings: Figure 1 is a 30 top plan view of bed mechanism involving my invention. Fig. 2 is a longitudinal section on the line 2—2 of Fig. 1. Fig. 3 is a somewhat similar view, some of the parts being omitted and certain additional parts being illustrated. Figs. 4 and 5 are trans- 35 verse sections on the lines 4—4 and 5—5 respectively of Fig. 1. Fig. 6 is a longitudinal section on the line 6—6 of Fig. 1.

Like characters refer to like parts throughout the several figures, which it will be ob- 40 served are on different scales.

The machine shown involves in its organization a traveling bed as 10 which reciprocates in the present instance, in a horizontal path after the manner substantially shown 45 in Letters Patent No. 843,535, granted February 5, 1907 to James W. Hoag, to which reference may be had. This bed is supported by complementary side rails as 11 sustained after the customary practice, by the frame- 50 work (not shown) of the press. It should be noted at this point that one of the primary purposes of the present invention is the shifting of a form-carrier by which the 55 form or type can be carried toward and from the printing plane or zone, and preferably,

although not necessarily the form-carrier is movably mounted upon the bed 10 and at proper points in the travel thereof is caused to rise and fall. It is conceivable, of course, that the form might be stationary upon the bed, and in this event the bed itself would be shifted in addition to its traveling movement; as a matter of fact it is not essential that the form be upon the bed, although this is advantageous. A form carrier such as 60 meets my conditions is that denoted in a general way by 12 and as shown, it is disposed within the bed 10 which may as illustrated be of substantially rectangular shape. This carrier 12 in the showing made, sus- 65 tains the form which may be of any suitable nature, and it is caused to move in alterna- 70 tion, by wedge means as will hereinafter appear, upwardly and downwardly, the first mentioned movement being accomplished to 75 secure an impression upon paper carried by a cylinder (not shown), the type or form being inked when the bed is in an upper position. The bed and form-carrier and their 80 movements as will be inferred, are fully set forth in the Letters Patent to which I have alluded, and therefore require no further 85 description.

As already intimated the form-carrier 12 is raised and lowered by wedge means and 90 in the organization represented this wedge means comprises a carrier such as the saddle denoted in a general way by 13 and which is illustrated as made up of companion side-bars 14 and a cross-bar 15 united with the 95 side bars between the ends thereof, the saddle as a whole being of approximately H- 100 form in plan. The bed 10 is provided in- 105 teriorly thereof with inwardly-extending flanges or webs 16 constituting suitable sup- 110 porting means for the side-bars 14, although said side-bars as illustrated, do not directly rest on said flanges, being directly supported by the duplicate plates 17 fitting in channels 18 in the upper sides of the two supporting flanges 16, and borne by adjusting screws 19 tapped through said flanges. The several adjusting screws 19 of which there may be any suitable number such as two at each side, can be utilized to accurately adjust and level 105 the saddle 13. As will hereinafter appear the saddle 13 is shifted with respect to the bed 10, and during this relative shifting movement the wedge means to which refer- 110 ence has been briefly made, acts to cause the

rising and falling of the form-carrier 12 on or in the bed.

The side-bars 14 are shown provided at or near their opposite ends with wedges 20 suitably fastened thereto, while the form-carrier 12 has similarly fastened to its under side, coöperating wedges 21, there being as shown four wedges on the saddle 13 and a corresponding number on the form-carrier 12, the two sets of wedges as will be understood coacting to effect the rising and falling of the form carrier. The wedges in addition to their bevel or angular faces also have horizontal or rest portions. As will hereinafter appear the form-carrier 12 has three distinct positions, and when in the upper and intermediate positions the type or form is inked, so that when the form is moved from the intermediate position to the upper position, an impression of the inked form upon the sheet or equivalent carried by the cylinder is made. I might add that when the form carrier is in its lowermost position the form is not inked; the inking mechanism, however, forms no part of the present application. I will also hereinafter describe the means for operating the wedge-carrier or saddle 13 with respect to the form-carrier, although I might note at this time that if the saddle 13 be moved to the right in Fig. 2 the form-carrier 12 through the co-operating sets of wedges 20 and 21, will be raised whereas when the saddle is moved in the opposite direction the form-carrier automatically lowers. The form-elevating movement is accomplished in the present instance, from the power-shaft of the machine, while the opposite throw is secured by spring means. The power-shaft is denoted by 22 and fastened to it is a spur-gear 23 which receives motion from a pinion, (not shown). The spur-gear 23 is illustrated having a wrist or crank pin 24 to which is loosely jointed the inner end of the connecting-rod 25 or pitman 25, having a pivotal connection with the stub-shaft 26 supported by the bracket 26' on the bed 10, said rod having at or near the shaft 26 the crank arm 27, the purpose of which will be hereinafter explained. It will be evident that as the spur gear or its equivalent 23 rotates the rod 25 and hence the bed 10 will be reciprocated and also that the arm 27 will be rocked or oscillated. Said arm 27 terminates in a cross head 28 to which are shown pivoted similar links 29 jointed at their inner ends to pivots or journals 30 extending laterally from the block 31, the wedge saddle 13 being provided with bearings 32 having suitable ways for supporting said block 31 and a companion block 33 for horizontal sliding movement. To the journals 30 are pivoted the links 34 likewise connected with the rocker 35 between the ends of the latter, the upper portion of said rocker being bowed or

cranked for the passage of the connecting rod 36, the purpose of which will be herein-after explained. Rigidly fastened to the upper end of the rocker 35 are the journals 37, the bed 10 having suitable bearings to receive said journals 37 for oscillatory motion. Pivoted in a fork at the lower end of the rocker 35 is a link 38 likewise jointed to the reciprocatory block 33. It will, therefore, be apparent that when the shaft 26 is rocked the blocks 31 and 33 through the de-scribed connections therewith will be simultaneously reciprocated and that the amount or degree of movement of the block 33 will be greater than that of the block 31 for a purpose that will be hereinafter obvious. When at least one of said blocks is locked to the saddle, the saddle will be operated in one direction by and on the movement of said block, return movement of the saddle being accomplished by independent means.

To lock the blocks to the saddle I have shown latch mechanism comprising the latches 39 and 40, the latch 39 being constantly active during printing or normal operation of the press, while the latch 40 is merely employed when the press is to be thrown into action being inoperative during printing, although as will hereinafter appear said latch 40 may be operated to shift the complemental latch 39 to a releasing position when the form raising mechanism is to be put into an inactive relation. The latch 40 is shown as rigid with the shaft 41 supported for rocking motion by the bearings 32, the latch 39 being loosely mounted on said shaft 41 and being movable to block-engaging position by a spring 42 connected therewith and also with some suitable relatively fixed part of the saddle or form-operating member 13. The latch 40 is also spring operable, the spring 40' (Fig. 4) connected with the arm 40' on the shaft 41 being shown for such purpose. It is possible, of course, that I might employ but a single block and a coöperating latch or their equivalents, but by duplicating the same I can prevent lost motion and insure smoothness of action of the wedge-saddle 13 and the form carrier.

As already intimated during printing, the power-operable block 31 when latched to the saddle 13 by the latch or pawl 39 serves to move said saddle 13 in one direction. The rod 36 connected rigidly with the saddle 13 and to which I have already referred, plays a part in effecting the return movement of the saddle, the power operable block 31 and latch 39 in the present instance normally advancing the saddle 13 or moving the same to the right in Fig. 2, while the rod and its adjuncts, retract said saddle. The rod 36 extends into the tube or casing 43 rigidly mounted on the bed 10 and to the forward end of said rod is connected one end of the

coiled spring 44 in said casing, the opposite end of said spring being connected with a pin 45 projecting through the forward wall of the casing or tube 43 and held against 5 displacement by the holding and check nuts 46. It will be assumed that the parts (except the latch 40) are occupying the positions indicated in Fig. 2, the latch 39 being in engagement with the block 31 and the 10 arm 27 being at its extreme left throw. As said arm 27 moves toward the right, the block 31 through its described connections therewith is carried in a similar direction and engaging the latch 39 moves the saddle 15 13 therewith, the spring 44 being stretched during such action. When the arm 27 completes its stroke to the right the spring 44 will return the wedge-saddle 13 to its primary position, at which time the arm 27 is 20 moved toward the left by the shaft 22 as already set forth. As the saddle 13 is advanced the form 12 is raised, said form dropping on the return or opposite movement of the saddle. 25 The shaft 41 to which the latch 40 is keyed, is shown having rigid therewith a lever or arm 50 which may as shown be equipped with an anti-friction roller 50' adapted as the saddle 13 reciprocates to 30 travel upon a rail or way 51 which as will hereinafter appear has three distinct positions. Said rail is shown having near its opposite ends cam slots 52 through which extend projections 53 on the framing of the 35 machine and as also having a pin 54 adapted to enter the fork of the rock lever 55 supported on said frame and adapted to be actuated in any desirable manner. The rail 51 is shown as occupying its lowermost position 40 in Fig. 2. By swinging the arm or lever 55 one step to the right said rail will be elevated to the position it occupies during printing, and by moving said lever or arm a second step said rail will be elevated its 45 maximum extent to thereby move the latch 40 to block-releasing or ineffective position said latch 40 when thus operated, moving the latch 39 to block-releasing position so that the blocks 31 and 33 can be operated 50 with respect to and on the saddle in which event the latter will not be shifted but will remain relatively at rest, this latter relation being assumed when the form-elevating mechanism is to be thrown out of action. 55 The latch 40 is shown furnished with an extension 56 adapted to engage the pin 57 on the co-operating latch 39 when the form-operating mechanism is to be thrown out of action. 60 It will be understood that when the form-elevating mechanism is out of action, (the saddle 13 at this time being at rest notwithstanding the fact that the shaft 26 is being rocked,) the rail 51 will be in its uppermost 65 or tripping position to which it has been

moved by the rock arm 55, acting through the primary agency of a hand lever (not shown). As said rail 51 is moved to said uppermost position, it lifts the latch 40 to its extreme uppermost or third position and as the latch 40 is thus operated the extension 56 thereon, moves the latch 39 to its tripped position, the consequence being that the two blocks 31 and 33 will reciprocate idly on the saddle 13, without actuating the latter as both 70 latches are tripped. In said Fig. 2, however, the saddle 13 is not at the extreme end of its retractive or backward stroke, it being assumed that said saddle is being moved in said direction by the spring 44. With 75 the two latches tripped they with the saddle will occupy a position somewhat to the left of that they are shown as occupying in Fig. 2. To throw the form-elevating mechanism into action therefore, the following procedure will be adopted: The rail 51 will be moved to its lowermost position so that the spring 40" can pull down the latch 40 to the full line position in Fig. 2 and at the same 80 time the latch 39 will be moved by the spring 42 to block-engaging position. As already 85 intimated the saddle 13 is now at the extreme end of its retractive or backward stroke; when it is there is considerable space between the block 33 and the latch 40. As the 90 arm 27 swings to the right the two blocks 31 and 33 are carried therewith until the block 33 comes in contact with the latch 40 at which point the saddle 13 is moved forward. When the two blocks and saddle have nearly 95 reached the front end of the stroke, the latch 39 is moved behind the catch portion of the block 31, the active portion of said latch 39, however, being carried a short distance beyond the catch portion of said block 31 so 100 as to insure proper latching, this condition being due to the fact that the stroke of the block 33 is greater than that of the block 31, said latch 39 being carried to said particular position through the joint action of the 105 block 33 and latch 40. As soon as the active portion of the latch 39 is in position to engage the catch portion of said block 31 the latch 40 is elevated to its central position. On the back stroke of the saddle the latch 39 110 comes in contact with the block 31 causing a slight knock. To eliminate this knock the latch 40 is elevated to its center or intermediate position or that it occupies during printing as shown by dotted lines in Fig. 2 at which time the extension 56 rests against the pin 57. When the latch is in said central position it is out of the path of the co-operating block 33. During printing, therefore, the block 31 and latch or pawl 39 are 115 in action, it being evident that at this time the rail 51 is in its central position, being adapted as it is moved from its lowest to its central position to elevate said latch 40 to the dotted line position in Fig. 2. By mov- 120 125 130

ing the rail 51 to the third or uppermost position, the latch 40 is further lifted, thereby depressing the latch 39 and disengaging the same from the block 31, so that when the block 31 and companion block 33 are advanced they will not operate or advance the saddle 13, the result being that the form elevating mechanism is thrown out of action. The block 33 and coöperating latch or pawl 40 present therefore a convenient means for automatically positioning the latch or pawl 39 with respect to the block 31, and it will be understood that after said block 31 and pawl 39 are thus relatively positioned, the latch 40 is thrown out of action or moved to its intermediate position as shown by dotted lines in Fig. 2. It should be explained that said latch 40 has three positions, the lowest position being shown by full lines in Fig. 2, and the intermediate position by dotted lines in the same view. When said latch 40 is in its third position it trips, as already described, the companion latch 39. The latch 39 has merely two positions, one an operative position when it is in the path of the block 31, and the other a trip or releasing position. It should be noted that the form is elevated when the parts are in their forward positions, while it is caused to lower when they are in their backward positions. By forward motion I mean the movement of the bed 10 and form carrier 12 toward the right in Fig. 1, the backward movement being just exactly opposite to this.

35 What I claim is:

1. The combination of a form carrier, a form operating member, a power operated member reciprocatory on said form operating member, a latch coöperative with the second member, and automatic means for relatively positioning said second member and latch whereby said second member and said latch can engage each other to latch said second member to said form operating member to shift the same.

2. The combination of a form carrier, a form operating member, a pair of members on said form operating member, means for reciprocating said pair of members, and latches for engaging the respective members of said pair, one member of said pair of members and its coöperating latch being adapted to automatically relatively position the other member of said pair and its latch and said other member and its latch when engaged serving to shift the form operating member.

3. The combination of a traveling bed, a form-carrier on said bed, a form-carrier operating member coöperative with the form carrier, a movable member on the form-carrier operating member, a latch on the form-carrier operating member, for latching said movable member thereto, and a trip device for said latch.

4. The combination of a traveling bed, a form-carrier on said bed, an operating member for said form carrier, a movable member on said operating member, a latch on said operating member, for connecting said movable member to said operating member whereby said movable member will serve to shift said operating member in one direction, and independent means for moving the operating member in the opposite direction. 70

5. The combination of a traveling bed, a form carrier on said bed, an operating device for said form-carrier, a movable member on the operating-device, a latch for connecting said movable member with the operating device to cause the movement of the latter in one direction, and spring means for moving the operating-device in the opposite direction. 80

6. The combination of a form carrier and a form operating member provided with co-operating wedges, a movable member on the form operating member, means for locking said movable member to the form operating member to move said form operating member in one direction, and operating means for imparting a return movement to said form operating member. 90

7. The combination of a form carrier, a form operating member, a movable member on the form operating member, a latch for locking said movable member to said form operating member to move the latter in one direction, independent means for imparting a return movement to the form operating member, and a rail, the latch having a projection to travel upon said rail and said rail being shiftable to trip said latch. 100

8. The combination of a form carrier, a reciprocatory form operating member, a movable member on the form operating member, a latch for locking said movable member to said form operating member to cause the movement of the latter in one direction, independent means for imparting an opposite movement to said form operating member, a shaft to which said latch is connected, an arm connected with said shaft and provided with an anti-friction roller, and a rail on which said roller travels, said rail being shiftable at will to trip said latch. 110

9. The combination of a traveling bed, a form carrier on said bed, a reciprocatory form carrier operating member on the bed, a movable member on the form carrier, power operated means for reciprocating said second member, a latch for locking said second member to the form carrier operating member to cause a movement in one direction of said form carrier operating member, and independent means for moving the form carrier operating member in the opposite direction. 120

10. The combination of a traveling bed, a form carrier on said bed, a form carrier op- 130

erating member also mounted on the bed, a pitman connected with the bed for reciprocating the same and provided with a crank arm, a block on said form carrier operating member, means operative from said crank arm for reciprocating said block, means for latching said block to the form carrier operating member to move the same in one direction, and independent means for moving 10 said form carrier operating member in the opposite direction.

11. The combination of a traveling bed, a form carrier on said bed, a form carrier operating member also on the bed, a block supported by the form carrier, a rocker linked to the block for reciprocating the same, means for oscillating said rocker, a latch for connecting said block to the form-carrier operating member to move the latter in one 20 direction, and independent means for moving said form carrier operating member in the opposite direction.

12. The combination of a form-carrier, a form-operating member, a reciprocatory member on said form-carrier operating member, a latch for latching said reciprocatory member to said form-carrier operating member to move the same in one direction, independent means for moving said form-carrier operating member in the opposite direction, and means for automatically relatively positioning said reciprocatory member and latch.

13. The combination of a form-carrier, a form operating member, a pair of blocks on said form-carrier operating member, means for reciprocating said blocks and for giving to one of them a greater degree of movement than the other, latches for engaging the blocks, one block and latch being adapted to automatically relatively position the other block and latch and the latter when engaged serving to move the form-carrier operating member in one direction, and independent 40 means for imparting an opposite movement to said form-carrier operating member.

14. The combination of a form carrier, a form operating member, a pair of members on said form carrier operating member,

means for reciprocating said pair of members, latches for engaging the respective members of said pair, one member of said pair of members and its coöperating latch being adapted to automatically relatively position the other member of said pair and its latch and said other member and its latch when engaged serving to move the form carrier operating member in one direction, and independent means for imparting an opposite movement to said form carrier operating member.

15. The combination of a form carrier, a form operating member, a second member on said form carrier operating member, a third member on said form carrier operating member, means for reciprocating said second and third members, latches coöperative respectively with the second and third members, the third member and its latch being adapted to automatically relatively position 70 the second member and its latch, and said second member and latch when engaged serving to move the form carrier operating member in one direction, independent means for imparting an opposite movement to said 75 form carrier operating member, and means for tripping at will the latch of the third member, the latch of the third member when tripped having means for tripping the latch of the second member.

16. The combination of a form carrier, a form operating member, a power operated member reciprocatory on said form operating member, a latch coöperative with the second member, and automatic means for 85 relatively positioning said second member and latch whereby the second member and latch can engage each other to latch said second member to said form operating member to move the same in one direction, and 90 independent means for moving the form carrier in the opposite direction.

In testimony whereof I affix my signature in presence of two witnesses.

EDWARD J. F. REA.
